UNITED STATES PATENT OFFICE.

OTTO EICK, OF ST. LOUIS, MISSOURI.

DESIGN FOR A RUBBER BRUSH.

46,592.

Specification for Design.

Patented Oct. 27, 1914.

Application filed July 31, 1914. Serial No. 854,410. Term of patent 14 years.

To all whom it may concern:

Be it known that I, OTTO EICK, a citizen of the United States, and a resident of St. Louis, in the State of Missouri, have invented a new, original, and ornamental Design for Rubber Brushes, of which the following is a specification, reference being had to the accompanying drawing, forming part thereof.

In the drawing, the figure is a front elevation of a brush illustrating my new design.

I claim:

The ornamental design for a rubber brush, as shown.

OTTO EICK.

Witnesses:

SYDNEY EICK,
G. H. LASAR.
